UNITED STATES PATENT OFFICE.

JOHN MOORE, OF PROVIDENCE, RHODE ISLAND.

BUTTON OR STUD.

SPECIFICATION forming part of Letters Patent No. 278,724, dated June 5, 1883.

Application filed December 31, 1881. (No model.)

To all whom it may concern:

Be it known that I, JOHN MOORE, of Providence, in the State of Rhode Island, have invented a new and useful Button or Stud; 5 and I do hereby declare that the following specification, taken in connection with the drawings making a part of the same, is a full, clear, and exact description thereof.

Figure 1 shows my improved button with 10 the shoe tipped. Fig. 2 is a section of post and shoe through the line *x x*. Fig. 3 shows side and edge of post. Fig. 4 shows top and edge of spring. Fig. 5 is a view of the inner disk.

15 My invention relates to that class of buttons called "non-separable," and has for its object the production of a button which will be easier of adjustment and more nearly perfect in its operation than those now in use; and it 20 consists in the construction and arrangement of the post, spring, and shoe, as hereinafter described.

In the drawings, A is the front of the button; B, the post; C, the shoe; D, the spring, 25 and E an inner disk. The post C is attached to the front A in the usual manner, and has at its outer end a slot, *e*, the sides of which project horizontally, partially closing the opening and forming lips *ff*. The spring D 30 is raised in the middle, and the disk E is cut out to permit the bearing-surface of the spring to come in contact with the under side of the shoe C. The disk E and the spring D are retained in place by turning over the edge of 35 the shoe C.

In putting the several parts together the disk E is first placed in the shoe C. The spring D, which is wider than the outlet to the slot *e*, is then put through until the square

40 lips or prongs *ff* rest in the raised or inverted **U**-shaped cavity, when the spring D is placed in position against the under side of the shoe C, and fits into and closes the open parts of the disk E. The edge of the shoe C is then turned over upon and holds the disk E and spring D 45 securely in place, and at the same time connects the whole with the post, after which the post is attached to the front A. The lips *ff* are confined between the **U**-shaped spring and the narrow or connecting portion of the disk 50 E. The sides of the **U**-shaped cavity are not exactly straight, but diverge slightly toward the shoe.

To insert the button the shoe is turned as 55 in Figs. 1 and 2, and passed through the button-hole. This being done, sufficient pressure is exerted upon the edge of the shoe by the finger to turn or bring it to the position shown by the dotted lines, Fig. 2, which secures the button in place. The lips *ff* being square, 60 and the place within which they are confined nearly so, it will be readily seen that the edges of the lips *ff* in turning, as the position of the shoe is changed in either direction, will raise the spring D, which will again find its contact 65 with the next flat surface of the lips *ff* presented to it.

What I claim as my invention, and desire to secure by Letters Patent, is—

In a button, the shoe C, provided with the 70 disk E, having its middle portion cut away, as shown, and the spring D, adapted to receive the end of the post, all substantially as shown and described.

JOHN MOORE.
